(57) **CLAIM**

The ornamental design for a toothed leveling rake, as shown and described.

DESCRIPTION

FIG. 1 is a front perspective view of a toothed leveling rake, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the toothed leveling rake in a combined state thereof; and,

FIG. 10 is an enlarged detail view of area 10 in FIG. 1.

The broken lines in the drawings illustrate the portions of the toothed leveling rake, which form no part of the claimed design.

The dash-dot-dash broken lines encircling the enlarged views are for annotative purposes only and form no part of the claim thereof.

The toothed leveling rake is shown with a symbolic break in FIG. 1-10. The appearance of any portion of the article between the break lines forms no part of the claimed design.
